UNITED STATES PATENT OFFICE

134,469

DESIGN FOR A MARINE CRAFT

Ellery L. Wood, Chicago, Ill., assignor of one-half to Ira J. Ingraham, Evanston, Ill.

Application April 20, 1942, Serial No. 106,632

Term of patent 7 years

To all whom it may concern:

Be it known that I, Ellery L. Wood, a citizen of the United States and residing at Chicago, county of Cook and State of Illinois, have invented a new, original, and ornamental Design for a Marine Craft, of which the following is a specification, reference being made to the accompanying drawings forming a part thereof.

Fig. 1 is a top plan view of a marine craft showing my design;

Fig. 2 is a side elevational view;
Fig. 3 is a front elevational view;
Fig. 4 is a rear elevational view;
Fig. 5 is a longitudinal sectional view to show the shape of the craft between the hulls; and
Fig. 6 is a bottom plan view.

I claim:

The ornamental design for a marine craft, substantially as shown.

ELLERY L. WOOD.
